NECKTIE RACK

Edward W. Franklin, Hyattsville, Md.

Application October 12, 1951, Serial No. 251,039

2 Claims. (Cl. 211—87)

1

This invention relates to necktie racks such as are adapted to support a plurality of neckties, and from which a tie may be selected and readily removed.

The object of the invention is to provide a rack of the type mentioned in which a large number of ties may be individually supported upon the rack, moved laterally with respect to adjacent ties for the purpose of inspection and choice, and the chosen tie removed from the rack, all without injuriously rubbing or marring any of the ties thereon.

A further and particular object of the invention is to provide a rack of the class mentioned in which the ties are each supported upon a separate suspension member, said members being slidably mounted upon a supporting slide-bar, and of such construction that the individual suspension members cannot rotate on the bar and cannot be accidentally displaced therefrom, but may be readily removed from and replaced on the bar as desired.

A further object of the invention is to provide a device as above stated to which suspension members may be readily added for additional ties as found necessary.

A further object of the invention is to provide a tie rack as stated in which the slidable suspension members may be of different colors to correspond to the color of the tie to be supported thereon so as to facilitate the selection of the desired tie.

Other objects will appear hereinafter.

The invention will be more readily understood by reference to the accompanying drawings forming a part of this specification and in which,

Fig. 1 is a perspective view of a necktie rack embodying the invention, two suspension members being illustrated on the slide-bar;

Fig. 2 is a detail rear elevation of one end of the rack including several suspension members, and illustrated upon an enlarged scale;

Fig. 3 is a detail cross section taken through the slide-bar on the line 3—3 of Fig. 2, and illustrating a suspension member being placed on or removed therefrom;

Fig. 4 is a fragmentary front elevation of the rack, illustrating the suspension members in various colors; and

Fig. 5 is a detail perspective view of one end of the supporting slide-bar illustrating a slight modification thereof.

Referring to the drawings, 10 indicates the supporting slide-bar, and 11 the suspension members slidably mounted thereon. The bar 10

2

is preferably straight throughout the major portion of its length, and angularly bent adjacent the ends as at 12, terminating in attaching lugs 13. The bar 10 is provided adjacent its end or ends with a pair of notches 14 and 15 extending inwardly from the upper and lower edges of the bar respectively and in vertical alignment with each other for a purpose hereinafter described. The bar 10 may be of any preferred non-circular cross section so that the suspension members cannot rotate thereon and chafe the adjacent ties, as will be more fully described hereinafter.

Each suspension member 11 comprises a lower body portion 16 having a recess 17 extending inwardly from the front edge 18 thereof to receive the mid-folded portion of a tie, and an upper portion 19 having a recess 20 to receive the bar 10. The recess is preferably of the same non-circular configuration as the cross section of the bar 10 to prevent any rotary movement of the member 11 on the bar; and is sufficiently larger than the bar to permit easy sliding of the members thereon.

Depending from the top 19' of the upper portion 19 is a lug 21, and a similar lug 22 extends upwardly from the upper portion 24 of the body 16. The lugs 21 and 22 normally engage the inner face of the bar 10 to maintain said bar in the recess 20. The ends 21' and 22' of the lugs 21 and 22 respectively are spaced apart a distance slightly greater than the distance between the inner ends 14' and 15' of the notches 14 and 15 so that when a member 11 is brought into alignment with said notches it may be readily placed upon or removed from the bar 10, as illustrated in Fig. 3.

The portion of the member 11 below the recess 17 constitutes a horizontal arm 25 upon which a tie is hung, and the forward end thereof is provided with an upwardly extending lug 26 to prevent the tie from accidentally slipping from said arm.

A slight modification of the bar 10 is illustrated in Fig. 5, wherein the notches 14 and 15 are formed in the angularly offset portions or supporting arms 12 of the bar instead of in the main portion of the bar as illustrated in Figs. 1 to 4 inclusive.

To facilitate selection of a tie the several suspension members 11 may be of different colors to match the general tone of the tie to be supported thereon; and this is illustrated in Fig. 4 of the drawings. The colors may be incorporated in the material of which the members are made 55 when formed of plastic material; or may be ap-

plied as a coating, dye, paint or enamel when the members are manufactured of other materials such as wood or metal. The colored members 11 may be arranged in any desired order on the bar, such as having all of a color grouped together or they may be indiscriminately placed on the bar as illustrated in Fig. 4. In either manner, the eye will be quickly directed to the hangers having ties of the desired color sought. It is obvious that new suspension members may be readily added as required.

It is believed that the construction and use of the device will be clear from the foregoing description.

I claim:

1. In a necktie rack, a slide bar of non-circular cross section, in combination with a plurality of substantially flat tie suspension members, each of said members comprising a lower body portion having a tie receiving recess open at the front of said member, and an upper portion having a recess open at the back to receive said bar, said bar being provided adjacent each end with a pair of aligned notches extending inwardly from the upper and lower edges thereof, respectively, the edges and surface of said bar between said pairs of notches being smooth and unbroken, and a pair of lugs on each of said suspension members to normally engage the inner face of said bar to maintain said member on said bar, the ends of said lugs being spaced apart a greater distance than the distance between the inner ends of said notches.

2. In a necktie rack, a slide bar formed of a

flat strip of material bent rearwardly at its ends forming angularly disposed supporting arms terminating in attaching lugs, in combination with a plurality of tie suspension members each comprising a lower body portion having a tie receiving recess open at the front of said member, and an upper portion having a recess open at the back to slidably receive said bar, one of said supporting arms being provided with a pair of vertically aligned recesses extending inwardly from the upper and lower edges thereof, respectively, and a pair of lugs on each of said suspension members to normally engage the inner face of said bar to maintain the same on said bar, the ends of said lugs being spaced apart a slightly greater distance than the distance between the inner ends of said notches.

EDWARD W. FRANKLIN.
